Tuan Galaz INVENTOR
BY *Victor J. Evans* ATTORNEY

UNITED STATES PATENT OFFICE

JUAN GALAZ, OF LOS ANGELES, CALIFORNIA

ATTACHMENT FOR PNEUMATIC HAMMERS

Application filed November 9, 1928. Serial No. 318,237.

This invention relates to improvements in pneumatic hammers, the general object of the invention being to provide means for absorbing the shocks caused by the back stroke of the reciprocating member of the hammer, so that such shocks will not be communicated to the user.

Another object of the invention is to provide spring means and an air cushion for absorbing the shocks.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is an elevation, partly in section, of the rear portion of a hammer provided with my invention.

Figure 2 is a face view of the grooved ring member.

Figure 3 is an elevation of the sleeve.

Figure 4 is a sectional view of the plunger.

As shown in Figure 1, the handle carrying part 1 of the hammer is threaded to the body 2 in such a manner as to leave a space between the rear end of the body and said part 1, and a ring 3 fits in this space. The interior circumference of the ring forms a shoulder 4 which is engaged by a shoulder formed by a head 5 on a plunger 6, the front end of the plunger being closed. When the plunger is in its forward position, its rear end is flush with the rear face of the ring.

A sleeve 7, having perforations 8 at its center, has its front end fitting in the larger diameter of the ring and said sleeve extends through the part 1 and is held in place by a plug 9 fitting in a threaded socket 10 formed in the rear end of the part 1. The perforated part of the sleeve is located in the air chamber 11 of said part 1 so that some of the air can enter the sleeve through the perforations. This sleeve forms guiding means for the plunger and a spring 12 of the plunger

extends through the sleeve and bears against the plug 9. Thus the spring tends to hold the plunger with its head resting against the shoulder 4.

The front face of the ring 3 is formed with an annular groove 13 which is in communication with the air passages formed in the internal member 14 of the body and said ring is also formed with the air ports 15 which connect the groove with the ports 16 in the part 1 and which are in communication with the chamber 11.

Thus it will be seen that the reciprocating member 17 of the hammer, on its back stroke, will strike the plunger and force the same rearwardly against the action of the spring 12 and that after the head of the plunger passes the perforations 8 in the sleeve 7, air will be trapped between the head of the plunger and the plug 9 so that this air cushion will act in conjunction with the spring to resist the further backward movement of the member 17, so that the shocks incident to the backward movement of the member 17 are absorbed and are not communicated to the hand and arm of the user. As the member 17 moves forwardly, the spring 12 will return the plunger to its normal position.

The part 1 is locked against turning movement by a sleeve 18 slidably but non-rotatably mounted on the body 2 and connected with the forward end of the member 1 by the latches 19 carried by the sleeve 18 and engaging the notches 20 in the member 1. The sleeve 18 is held against rotary movement by the set screw 21 in the body 2 engaging a groove 22 in the forward end of the member 1.

As the sleeve 18 is prevented from rotating and is locked to the member 1 by the latches 19, it will be seen that said member cannot rotate and thus become loose without moving the latches to releasing position.

It is thought from the foregoing description that the advantages and novel features of the invention will be readily apparent.

It is to be understood that changes may be made in the construction and in the combination and arrangement of the several

parts, provided that such changes fall within the scope of the appended claim.

What I claim is:—

An attachment for pneumatic hammers including a handle carrying member having an air pressure chamber and a tubular portion to receive and be secured to a body for reciprocating the driving member actuated by air pressure from the chamber, an annular member positioned between the handle carrying member and the body, an annular shoulder on said annular member, a recessed plug removably secured to the handle carrying member, a sleeve seated in the recessed plug and engaging the shoulder and provided with apertures in communication with the air pressure chamber, a recessed plunger slideable in the sleeve to be moved in one direction by the driving member, a flange on the plunger to engage the shoulder to limit the movement of the plunger in an opposite direction, and a cushioning spring engaging the plug and seated in the recess of the plunger to retard the movement of said plunger in the first named direction, said plunger during the last named movement adapted to trap air between itself, the sleeve and the plug to absorb shocks from the driving member to the handle carrying member.

30 In testimony whereof I affix my signature.

JUAN GALAZ.
